LINE FEED ALARM DEVICE FOR SPROCKET FEED PRINTER

Raymond H. Kartasuk, Lincolnwood, and Robert G. Wampach, Roselle, Ill., assignors to Teletype Corporation, Skokie, Ill., a corporation of Delaware
Filed Mar. 7, 1961, Ser. No. 94,026
9 Claims. (Cl. 197—133)

This invention relates to line feed alarm devices and more particularly to line feed alarm devices for sprocket feed printing telegraph page printer apparatus.

It is an object of the present invention to provide an alarm device for indicating the failure of a printer to advance the web being fed by it, upon receipt of a line feed signal.

Another object of the invention is the provision of an apparatus which will indicate that the alarm device is not operating properly.

Still another object of the invention is to provide an alarm device for indicating that a feed sprocket for feeding a web of paper through a printing telegraph apparatus has failed to advance the web.

A feature of the present invention is the provision of an auxiliary sprocket driven by the paper, being fed by the sprocket feed wheel of a printer, for controlling an alarm device.

In accordance with one embodiment of the invention a printing telegraph page or form printer of the sprocket feed type is provided with a line feed alarm wherein, as the web of paper is fed step-by-step to the printing mechanism, it drives an auxiliary sprocket having fixed to it a cam drum, and the line feed bar which drives the regular paper feed sprocket of the apparatus has a pawl mounted on it for driving a ratchet wheel one step each time the line feed bar steps the regular paper feed sprocket one step. The cam drum on the auxiliary sprocket moves a retaining or check pawl out of operative association with the ratchet each time the auxiliary sprocket is rotated by the paper. In the event the paper is not advanced by the operation of the line feed bar or in the event that the supply of paper is exhausted, the auxiliary sprocket will not be stepped and consequently, the pawl on the line feed bar will move the ratchet through a plurality of steps to carry a switch actuator on it into operative relation to an alarm switch. The auxiliary sprocket is mounted on a latch lever that may be manipulated to raise the sprocket out of association with paper being advanced to the regular sprocket wheel, and when this operation occurs an auxiliary check pawl will be moved into association with the ratchet wheel thereby to check the return movement of the ratchet wheel and cause operation of the alarm switch after a predetermined number of feeding operations by the line feed bar.

A more complete understanding of the invention may be had by reference to the following detailed description when considered in conjunction with the accompanying drawings wherein:

FIG. 1 is a side elevational view of a portion of a printing telegraph apparatus showing the pertinent portion of the line feed mechanism and the alarm mechanism associated therewith;

FIG. 2 is a fragmentary plan view of the apparatus shown in FIG. 1 taken substantially along the line 2—2 of FIG. 1 in the direction of the arrows, and

FIG. 3 is a fragmentary sectional view taken substantially along the line 3—3 of FIG. 1 in the direction of the arrows.

Referring now to the drawings, wherein like reference characters designate the same parts throughout the several views, the alarm mechanism of the present invention includes an alarm switch 4, an auxiliary sprocket 5, a reset

2

lever assemblage 6 and a ratchet assemblage 7. The apparatus of the present invention is particularly adaptable to printing telegraph apparatus of the type illustrated in United States Patent No. 2,505,729, granted April 25, 1950 to W. J. Zenner and to United States Patent No. 2,667,256 granted January 26, 1954 to B. F. Madsen which discloses and claims the details of a line feed mechanism particularly useful in a structure such as that shown in said Patent No. 2,505,729. The disclosure of the two above-identified patents is incorporated herein by reference and made a part hereof.

In the above-mentioned patent to B. F. Madsen, No. 2,667,256 there is shown a gear 11 fixed to a platen 12 which, as illustrated in said Patent No. 2,667,256 is the usual smooth cylindrical platen but which could be provided with sprocket teeth 30 for feeding forms or other sprocket fed types of web. As described in said Patent No. 2,667,256 to B. F. Madsen, a pair of drive rack members or line feed bars 13 and 14 are designed to alternately engage with the teeth of the gear 11 to drive the gear 11. These line feed bars 13 and 14 are connected to eccentrics 16 and 17 mounted on a shaft 18 and when the shaft 18 is rotated, the line feed bars 13 and 14 will be rocked on a movable pivot 19 which carries a roller 21 that cooperates with slots 22 and 23 in the line feed bars 13 and 14. The roller 21, as clearly described in said Patent No. 2,667,256 to B. F. Madsen, is mounted on a bell crank lever 24 biased about a pivot 25 by a spring 26 and urged to engage an adjustable stop 27.

The alarm switch 4, auxiliary sprocket 5, reset lever assemblage 6 and ratchet assemblage 7 are mounted on a mounting plate 31 suitably attached to the framework 28 of the printer apparatus, a pair of mounting screws 32 being provided for mounting the plate 31. In the ordinary operation of the apparatus disclosed in the above-mentioned Patent No. 2,505,729 to W. J. Zenner rotation of the platen 12 will withdraw a web of paper 33 from a suitable supply thereof across a paper guide plate 34 to direct it to the platen 12. In the construction in accordance with the present invention, a slot 35 is formed in the paper guide plate 34 into which the teeth 36 of the auxiliary sprocket 5 may enter when the sprocket 5 is in the position illustrated in the drawings. The sprocket 5 and a restoring cam 37 are rotatably mounted on a stud shaft 38 which is fixed to a latch lever 40, the sprocket 5 comprising a ring suitably fixed on a shoulder 39 of the cam 37. The latch lever 40 is urged downwardly and to the right (FIG. 1) by a contractile spring 41 fixed to the mounting plate 31 and to the latch lever 40. An adjustable support 42 is adjustably mounted on the mounting plate 31 and will serve to support the latch lever 40 in the position shown in FIG. 1 where a bearing surface 43 on the latch lever 40 engages the adjustable support 42, or in a position where a guide surface 44 may rest on the support 42. The shaft 38 extends into a slot 45 formed in the mounting plate 31 whereby the shaft 38 and the auxiliary sprocket 5 and restoring cam 37 may be moved upwardly from the position shown in FIG. 1 to move the sprocket teeth of sprocket 5 out of slot 35 thereby to facilitate the insertion of a web of paper 33 into the apparatus.

The restoring cam 37 cooperates with the reset lever assemblage 6, a camming portion 50 of which bears on the restoring cam 37. The reset lever assemblage 6 comprises two portions 51 and 52 adjustably connected one to another by means of an adjustment screw 53 and the lever assemblage 6 is pivotally mounted on a pivot stud 54 suitably fixed to the mounting plate 31. The lever assemblage 6 is urged to rock in a clockwise direction (FIG. 1) about stud 54 by a contractile spring 55 fixed to the portion 51 of the lever assemblage 6 and to the mounting plate 31 thus, to urge the camming portion 50

of the assemblage 6 toward the restoring cam 37. The lower left-hand portion (FIG. 1) of the lever assemblage 6 has a check pawl 56 formed on it for cooperation with ratchet teeth 57 on the ratchet assemblage 7 which assemblage is rotatably mounted on a stud shaft 58 fixed to the mounting plate 31. The ratchet assemblage 7 has fixed to it a switch actuator arm 65 having a switch actuator 66 suitably fixed to it for cooperation with a switch button 67 on the alarm switch 4. The ratchet assemblage 7 is urged to rotate in a counterclockwise direction about the stud shaft 58 by a spring 68 attached to a projection 69 on the lever 65 to carry a projection 70 also formed on the lever 65 into engagement with a stop pin 71 fixed to the mounting plate 31. In addition to the ratchet teeth 57, the ratchet assemblage 7 is provided with two other sets of teeth 72 and 73. The teeth 72 of the ratchet assemblage 7 are positioned for cooperation with a pawl 74 which is pivotally mounted on the upper end of the line feed bar 13 and is normally urged to rock about a pivot 75 fixed to the bar 13 by a spring 76. The other set of ratchet teeth 73 are aligned, with a check pawl 80 that is pivoted on the stud shaft 54 and is urged to follow the movements of the reset lever assemblage 6 by a contractile spring 81 attached to the pawl 80 and the reset lever assemblage 6. This pawl is limited in its movement in a counterclockwise direction (FIG. 1) by a projection 82 on it engaging a bent-over portion 83 of the lever assemblage 6.

Operation

In the operation of an apparatus equipped with the line feed alarm mechanism of the present invention a web of paper 33 may be fed into association with sprocket teeth 30 of platen 12 of the printing apparatus by manually raising the lever 40 to move the surface 44 thereof into the position occupied by the surface 43 as shown in the drawings, thus, to lift the shaft 38 restoring cam 37 and auxiliary sprocket 5 upwardly to carry the teeth 36 of the sprocket 5 out of the slot 35 to permit free movement of the web of paper 33 underneath the auxiliary sprocket 5. After the paper has been fed across the plate 34 to engagement with the teeth 30 of the sprocket teeth 30 of platen 12, the lever 40 may be restored to the position shown in the drawings where the sprocket teeth 36 will be engaged in sprocket feed holes 85 in the web of paper 33. With the apparatus in this condition, that is, with web of paper engaging the platen 12 and auxiliary sprocket 5, the initiation of a printing operation may take place and each time the web 33 is advanced one step due to the reciprocation of the line feed bar 13, the pawl 74 will move the ratchet assemblage 7 one step. At each step of movement of the web of paper 33, the ratchet assemblage 7 will oscillate one step. However, if the auxiliary sprocket 5 is moved in a clockwise direction by the paper, the spring 68 will be permitted to snap the ratchet assemblage 7 back to the position shown in the drawings due to the fact that the cam 37 will cam the retaining or check pawl 56 of lever assemblage 6 out of engagement with the teeth 57 of the ratchet assemblage 7. Thus, for each step of movement of the web of paper 33 by the line feed bars 13 and 14, the ratchet 7 will be moved in a clockwise direction by the pawl 74 and then be returned in a counterclockwise direction (FIG. 1) to the position shown in the drawings.

In the event that the web 33 is not fed by the sprocket teeth 30 of platen 12 or the supply of paper is exhausted and as a result of the failure to feed the paper or exhaustion of the stock of paper the auxiliary sprocket 5 is not rotated in a clockwise direction (FIG. 1), the retaining or check pawl 56 will engage with successive ratchet teeth 57 and will thus prevent the spring 68 from returning the sprocket assemblage 7 to the position shown in the drawings. After a predetermined number of reciprocations are imparted to the line feed bar 13, four in the apparatus illustrated, the switch actuator 66 will be moved clockwise to engagement with the switch button 67 to

actuate the alarm switch 4 calling an operator's attention to the fact that the supply of paper 33 is exhausted or that the line feed mechanism is not operating properly. If a new supply of paper is to be placed in the apparatus, the lever 40 is manipulated to raise the restoring cam 37 and thereby rock the lever assemblage 6 counterclockwise (FIG. 1) to permit the ratchet assemblage 7 to move back to the position shown in the drawings. Whereupon, a new supply of paper may be placed in the apparatus and the lever 40 restored to the position shown in the drawings. If, by chance, the auxiliary sprocket and restoring cam are accidentally left in the upward position with the guide surface 44 engaging adjustable support 42, the check pawl 80 will be rocked into engagement with the teeth 73 on the ratchet 7 and if four steps of reciprocation are imparted to the line feed bar 13 before this condition is corrected, the check pawl 80 will cooperate with the ratchet assemblage 7 and the alarm switch 4 will be operated.

Although a specific embodiment of the invention has been shown in the drawings and described in the foregoing specification, it will be understood that the invention is not limited to the specific embodiment, but is capable of modification and rearrangement, and substitution of parts and elements, without departing from the spirit of the invention.

What is claimed is:

1. In a printer, line feed mechanism including a feed sprocket for advancing a web through the printer, a line feed member intermittently operable for imparting step-by-step rotation to said sprocket, a storage device driven one step by said member each time said line feed member is actuated, means for returning said storage device to a normal position, means normally driven by the web for causing operation of the returning means each time the line feed member drives the storage device one step, and alarm means actuated by said storage device following a predetermined number of operations of said member while the means driven by the web is not driven.
2. In a printer, line feed mechanism including a feed sprocket for advancing a web through the printer, a line feed member intermittently operable for imparting step-by-step rotation to said sprocket, a storage device driven one step by said member each time said line feed member is actuated, means for returning said storage device to a normal position, means normally driven by the web for causing operation of the returning means each time the line feed member drives the storage device one step, and alarm means actuated by said storage device when said returning means is inoperative for a predetermined number of operations of said line feed member.
3. In a printer, line feed mechanism including a feed sprocket for advancing a web through the printer, a line feed member intermittently operable for imparting step-by-step rotation to said sprocket, a drive pawl on said member, a ratchet driven from a normal position one step by said pawl each time said line feed member is actuated, means for returning said ratchet to its normal position, cam means positioned to be driven by the web for rendering the returning means operative each time the web drives the cam means one step, a switch actuating arm controlled by said ratchet, and alarm means actuated by said arm upon a predetermined number of operations of said ratchet coupled with failure of said cam means to be driven by the web.
4. In a telegraph printer, line feed mechanism including a feed sprocket for advancing a web through the printer, a line feed bar intermittently operable for imparting step-by-step rotation to said sprocket, a drive pawl on said bar, a ratchet driven one step from a normal position by said drive pawl each time said line feed bar is actuated, spring means for urging said ratchet to return to said normal position, a retaining pawl for holding said ratchet in a position to which it has been stepped by said drive pawl, an auxiliary sprocket driven by said web, cam means fixed to said auxiliary sprocket for disen-

gaging said retaining pawl from the ratchet each time the web drives the auxiliary sprocket one step, an alarm actuating lever fixed to said ratchet, and alarm means actuated by said alarm actuating lever upon a predetermined number of operations of said line feed bar coupled with failure of said auxiliary sprocket to be driven by said web.

5. A telegraph printer according to claim 4 wherein the auxiliary sprocket and cam means are mounted on a stud shaft that is bodily movable from a position where the auxiliary sprocket on it is in the path of the web to a position where the auxiliary sprocket is out of the path of the web and said retaining pawl is disengaged from the ratchet by movement of said auxiliary sprocket to facilitate inserting a web into the printer.

6. The combination according to claim 5 wherein said ratchet retaining pawl has a second pawl pivotally mounted on it for engagement with the ratchet when the stud shaft is moved to a position to carry the auxiliary sprocket out of the path of the web.

7. In a telegraph printer, line feed mechanism including a feed sprocket for advancing a web through the printer, a line feed bar intermittently operable for imparting step-by-step rotation to said sprocket, a drive pawl on said bar, a ratchet device driven from a normal position by said pawl one step each time said line feed bar is actuated, means for resiliently urging said ratchet to return to said normal position, a reset lever for blocking the return of said ratchet to normal position, means driven by the web for moving said reset lever out of blocking relation with respect to said ratchet each time the web drives the means driven by the web one step, and alarm means actuated by said ratchet if the reset lever is not moved out of blocking relation to the ratchet for a predetermined number of operations of said bar.

30
35

8. In a telegraph printer, line feed mechanism including a feed sprocket for advancing a web through the printer, a line feed bar intermittently operable for imparting step-by-step rotation to said sprocket, a drive pawl on said bar, a ratchet driven one step from a normal position each time said line feed bar is actuated, spring means for urging said ratchet to return to said normal position, a retaining pawl for holding said ratchet in a position to which it has been stepped by said drive pawl, an auxiliary sprocket driven by said web, cam means fixed to said auxiliary sprocket for disengaging said retaining pawl from the ratchet each time the web drives the auxiliary sprocket one step, an alarm actuating lever fixed to said ratchet, and alarm means actuated by said lever upon said lever being moved through a predetermined arc due to failure of the auxiliary sprocket to be driven by the web for a predetermined number of operations of the line feed bar.

9. A web feeding mechanism for telegraph printers including means for engaging a web to advance it through the printer, a line feed member intermittently operable for imparting step-by-step movement to said means engaging the web, means for engagement with the web to be driven by the web each time the web is advanced, a storage member movable one step by said line feed member each time said member operates, means for holding said storage member in the position to which it is moved, and means on the means driven by the web for disabling the holding means each time the means to be driven by the web is moved by the web.
